(57) **CLAIM**

The ornamental design for a gaming table with bet spot ornamentation as shown and described.

DESCRIPTION

FIG. 1 is a top view of a gaming table with bet spot ornamentation showing my new design; and, FIG. 2 is an enlarged view thereof corresponding to region 2 depicted in FIG. 1.

The uneven-length broken line framing a callout region in FIGS. 1 and 2 forms no part of the claimed design. The even-length broken lines depicting the diamonds and the remainder of the gaming table form no part of the claimed design. The unshaded areas form no part of the claimed design.

1 Claim, 2 Drawing Sheets

FIG. 1

FIG. 2
